UNITED STATES PATENT OFFICE.

HENDERSON RYAN, OF SEATTLE, WASHINGTON.

BUILDING CONSTRUCTION.

1,241,445.

Specification of Letters Patent. Patented Sept. 25, 1917.

Application filed July 1, 1916. Serial No. 107,031.

To all whom it may concern:

Be it known that I, HENDERSON RYAN, a citizen of the United States, residing at Seattle, in the county of King and State of Washington, have invented certain new and useful Improvements in Building Construction, of which the following is a specification.

This invention relates to improvements in building construction.

The object of the invention is the provision of an improved theater building containing a ramp or inclined walk leading to the balcony which crosses the foyer or ante-room to the rear of the main auditorium midway the length of the foyer and thus permits the foyer being positioned directly against the side wall of the building with the result of large increase in the seating capacity of the auditorium. Access to the balcony is greatly facilitated by the novel arrangement of the ramp as provided in my invention.

The invention consists in the novel construction of a theater building, and the adaptation, arrangement and combination of novel features therein, as will be fully described in the following specifications, illustrated in the accompanying drawings, and finally set forth in the appended claims.

In said drawings, Figure 1 is a horizontal sectional view of a building constructed in accordance with my invention, taken on line 1—1 of Fig. 3.

Fig. 2 is a view similar to Fig. 1, taken on line 2—2 of Fig. 3.

Fig. 3 is a vertical sectional view taken on line 3—3 of Fig. 1.

Fig. 4 is a view similar to Fig. 3 taken on line 4—4 of Fig. 1.

Figs. 5 and 6 are perspective views illustrating certain constructional details of the invention.

Referring to said drawings, wherein like reference characters indicate like parts in the several views, the reference numeral 10 indicates the front wall of a rectangular building, 11 the opposite rear wall, and 12 and 13 the connecting side walls, respectively. Said walls constitute the main structural elements of the building, although the front wall is largely of glass and of an ornamental character, 10¹ indicating the columns upon which the weight of the structure is carried.

Interiorly of the building as defined by

said walls, is a vertical wall 15 which is connected to the side wall 13 intermediate the intersection of the latter with the front and rear walls, and extends toward the opposite side wall and directed toward the front of the building at an inclination forming an obtuse angle upon the side adjacent the rear wall 11 and which, if projected to intersect an extension of the back wall 11, 65 would diverge from the latter at an angle of approximately thirty degrees.

Between the diverging walls 11 and 13 is the auditorium 14 consisting in a converging walled chamber whose narrower end 70 16 in proximity of the wall 13 is provided with a stage 17 and motion picture screen 18 which are directed symmetrically with respect to the major axis of the auditorium. Said stage and screen may desirably occupy 75 the larger portion of said narrow end of the auditorium, and the rows of seats 20 are, or may be, arranged in radiating lines, all of which converge upon the stage and screen.

The side walls 11 and 15 of the auditorium having a divergence of about thirty degrees and the screen being positioned at the smaller end thereof, all the seats occupying the entire auditorium may be arranged substantially in front of the screen to obtain a good view of the pictures being shown thereon with practically no observable distortion of the image being projected through the visual angle being oblique from 90 the axis of the beam of projection.

The angle of vision from the most extreme side seats will be less than fifteen degrees, which will not cause a noticeably distorted picture to be observed.

19 indicates a wing extension of said wall 15 that may extend to the wall 12 in lines rectangular thereto. Said wing does not extend to the lower or main floor but begins at the mezzanine floor and thence upwardly 100 to the upper floors or roof.

Referring further to the floor plan of the building, it will be seen that store-rooms 21, 22, 23 are provided forwardly of the wall 15 which are suitable for retail stores and owing to the said inclination of the wall 15 may all be of relatively long length or depth and increase in such depth as they are situated relative to the wall 13.

25 indicates the entrance and 26 the lobby 110 of the theater from which leads a foyer 27 extending in curved directions to the rear of

the auditorium, whereby access may be had to the aisles between the sections of seats. Said entrance and lobby are positioned toward the middle of the front of the building, 5 and an additional retail-store-room 28 may be provided between said entrance and the side wall 12.

A single ramp or inclined walk 30 is provided for attaining access to the balcony 31. 10 The lower entrance 32 to said ramp is upon the one side of said lobby near the entrance 25 and to the outer side of the foyer, and extends with a curved sweep upwardly in an inclined plane under an arch 33 formed in 15 the lower portion of wing wall 19, until about the mid-length of the rear end of the auditorium is reached, whereupon the ramp is given a relatively sharp bend, as at 35, and crosses overhead of the foyer and 20 thence extends in two oppositely directed branches 36 and 37 by easy curves to the opposite sides of the auditorium balcony.

The ramp is inclined with a rise of about one foot in six feet of length. Its lower end 25 32 is positioned forwardly in close proximity of the entrance 25 and considerably removed from the side wall 12, so that where its curved sweep at its lower end approaches said side wall 12, it has reached an elevation 30 that carries it well above the foyer. For a distance from the entrance, the side wall 41 of the foyer and the inner railing 42 of the ramp are in vertical alinement but at a point somewhat beyond the archway 33 35 formed by the lower edge of the wing-wall 19, when the ramp has reached an elevation to afford head-room in the foyer, the ramp continues in the same curved sweep to extend over the foyer, as at 45, while the foyer 40 is directed toward the side wall, as indicated in the dotted lines 46 in Fig. 2, and beyond the projected center axial line, approximately, of the auditorium, the foyer is positioned directly against the side wall 12 45 and extends thus to the rear wall 11 of the building.

In all other arrangements of ramps in theater buildings known to me, the ramp is positioned to the rear of the foyer and 50 extended to the opposite side of the auditorium; that is to say, what would be between the foyer as presented in the drawings, and the wall 12, and extended to close proximity of the rear wall 11, thus taking off val-

able seating capacity from the auditorium 55 and bringing the higher end of the ramp upon one side of the balcony, necessitating either a long return passage to reach the opposite side of the balcony, or another ramp to reach the opposite side of the balcony 60 more directly.

By the provision of the ramp as in my invention, and by crossing overhead the foyer at about its midlength, I am enabled to carry the foyer back to the side wall 12, 65 affording a much larger seating capacity and enable the patrons to reach the balcony by an easy grade upon either side by branch ramps 36 and 37 which are of equal 70 lengths.

It will be seen by reference to Figs. 5 and 6, that the provision of the ramp somewhat overhanging the foyer, as indicated by the construction angle 47, is not at all objectionable from an interior decorative point 75 of view and as has been most successfully demonstrated.

Having described my invention, what I claim is—

1. In a building of the class described, 80 including an auditorium on its main floor and a balcony, a foyer positioned at the rear of said auditorium having an entrance at one end of said foyer, and a ramp having its lower end positioned adjacent the entrance end of said foyer upon the side opposite from the auditorium, and crossing over said foyer at approximately the midlength of the foyer to afford access to the balcony. 85

2. In a building of the class described, including an auditorium on its main floor and a balcony, a foyer positioned at the rear of said auditorium having an entrance at one end of said foyer, and a ramp having its lower end positioned adjacent the entrance end of said foyer upon the side opposite from the auditorium, crossing over said foyer at approximately the midlength of the foyer and extending in branch inclined 95 approaches to afford access to either side of 100 said balcony.

Signed at Seattle, Washington, this 23rd day of June, 1916.

HENDERSON RYAN.
